RELEASING CLAMP

John Milton Jester, Washington, D. C.

Application September 28, 1932, Serial No. 635,273

19 Claims. (Cl. 248—64)

The invention relates to clamps for supporting high tension transmission lines and has for its general object the provision of a clamp which will grip a conductor or cable tightly under normal circumstances but which will release its grip upon the occurrence of a strain tending to move the clamp longitudinally in one direction or the other as for example in the event of breakage of the conductor.

It is well known that it is the practice to support a high tension conductor, or its equivalent, by means of clamps suspended from skeleton towers which are frequently located long distances apart with the result that there is a very great span between successive clamps used. In mountainous country and in fact in other places, it may occur that an excessive strain comes upon one or more spans for instance as the result of the accumulation of ice or sleet upon the conductor. In such an event it is obvious that the greatly increased weight of an individual span or a number of spans will bring a tremendous strain upon the tower beyond the over-weighted span, there being quite a marked tendency to cause the tower to overturn. Under such circumstances and also in the event of breakage of the conductor it is highly desirable to provide means whereby the clamp may release the conductor and permit it to slip through until the strains are equalized.

It is with the above facts in view that I have devised the present invention which has for an object the provision of a novel and improved clamp of this general type and one which will permit a limited displacement of the clamp and its supporting element from the normal position without releasing the conductor, it requiring a tilting or swinging displacement beyond a certain predetermined limit to effect the release.

A very important object of the invention is to provide a clamp of this character embodying the minimum number of parts, which will be entirely free from any springs and in which the parts are assembled and held together without any necessity for the employment of securing elements such as bolts, rivets or anything else of a similar nature.

Yet another object is to provide a clamp which has a pivotal connection with a suspension yoke or other support, the axis of the pivot moreover intersecting the conductor so that in the event of swaying of the clamp and its support there will be no rocking or tilting tendency.

Still another object is to provide a clamp of this character in which the gripping action upon the conductor takes place at the center, the end portions of the clamp body and also the movable clamping member being curved and flared outwardly away from the conductor so as to avoid contact therewith and the bringing of bending

strains upon it in the event that the conductor vibrates or "dances".

A further object is to provide a clamp of this character which on account of the fewness of parts will be extremely simple and inexpensive to make, easy to install, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a view partly in side elevation and partly in longitudinal section showing the clamp, the released position of the trip member being shown by dot and dash lines and its operative, or effective position being shown by full lines.

Figure 2 is a central vertical cross sectional view with fragments in elevation.

Figure 3 is a detail plan view of the movable clamping member.

Figure 4 is a side elevation thereof.

Figure 5 is an elevation of the trip, and

Figure 6 is an elevation thereof taken at right angles to Figure 5.

Referring more particularly to the drawing I have shown the clamp as comprising a main supporting body 10 preferably longitudinally curved and reinforced at its underside by longitudinal and transverse webs 11 and 12, respectively. This body is formed with a transversely curved seat 13 for the reception of the conductor 14 and it will be observed that the ends of this seat or grooved portion are flared outwardly so as to avoid contact with and the bringing of bending strains upon the conductor. The sides 15 of the main body of the clamp are prolonged upwardly an appreciable distance above the conductor and are formed near one end with circular holes 16 communicating with reduced slots 17 opening out at the upper edges. Moreover at their central portions the sides 15 are formed with circular holes 18 communicating with reduced slots 19 which likewise open out at the upper edges.

For suspending the device, I have shown the opposite sides of the main body 10 as formed with trunnions 20 which are rotatably received within holes 21 in the lower ends of suspension links or the like 22 which are adapted to be hung from the lower end of a string of insulators as is a customary procedure. The holes 21 are vertically elongated so as to permit passage, when installation is being effected, of heads 23 on the ends of the trunnions, which heads overhang downwardly and project below the lower edges of the openings 21 so that there will be no danger of dis-

connection of the clamp from the suspension means.

The parts thus far described merely support the conductor. To effect clamping thereof I provide an upper clamping member 24 which has its underside somewhat concaved to provide a seat 25 conforming substantially to the conductor. One end of this clamping member is free while the other end is formed at opposite sides with transverse lugs or projections 26 having a thickness corresponding substantially to the width of the slots 17 and having a length corresponding substantially to the diameter of the holes 16, the ends being moreover curved as shown at 27 so as to fit conformingly against the walls of the holes 16.

To mount the movable or upper clamping member 24 or connect it with the main body of the clamp it is necessary to position it in a substantially vertical position and insert the lugs or projections 26 downwardly through the slots 17 until they enter the holes 16 whereupon this member is swung down into contact with the conductor, the lugs 26 rotating within the holes 16 as this is done. Obviously the clamping member cannot get out of place unless it be swung upwardly into vertical position so that the projections 26 can be withdrawn through the slots 17.

The means cooperating with the clamping member 24 for holding the same in gripping relation to the conductor is represented as comprising a trip cam 28 having its upper portion of V-shape or formed with divergent arms 29 which define the V-shaped opening 30 between them. At opposite sides this trip cam is provided with lugs or projections 31 having their major dimension extending transversely. These projections are of substantially the same width as the slots 19 and have a length of substantially the same diameter as the holes 18, the ends being moreover arcuate as shown at 32 so as to fit conformingly against the walls of the holes 18.

To effect mounting of this trip cam it must be introduced between the sides 15 in a horizontal position as shown by the dot and dash lines in Figure 1 so that the projections 31 can be passed down through the slots 19 and caused to enter the holes 18, after which the trip cam is swung into the upright position shown by full lines. The lower end of this trip member is of cam shape as shown at 33 in Figure 5 so that when it is turned from the horizontal to the vertical position shown in Figure 1 it will exert a camming action upon the upper clamping member 24 and force the same into gripping engagement with the conductor.

As long as the trip member is in its upright position the clamping action is maintained, it being clear that to effect release it is necessary to tilt this member 28 to one side or the other of its normal or vertical position. To effect such release when an excessive strain comes upon the conductor at one side or the other of the clamp I provide the confronting faces of the links 22 with lugs 34 which are located within the V-shaped opening 30 of the trip cam normally in spaced relation to the inner faces of the arms 29 thereof so that the clamp and its suspension link may have a limited swinging movement without releasing the conductor. However, it will be seen that in the event of overloading or breakage of the conductor at either side of the clamp the resultant excessive movement of the clamp and its suspension link will cause the lugs 34 to engage one or the other of the arms 29 and consequently force the trip cam 28 out of its normal or upright position

whereupon by virtue of the shape of the cam surface 33 the pressure exerted upon the clamping member 24 will be relieved, thus releasing its clamping engagement upon the conductor so that the conductor may slip through the clamp until the pressure along the conductor is equalized.

From the foregoing description and a study of the drawing it will be apparent that I have thus provided an efficient conductor clamp which is capable of automatically releasing the conductor upon the occurrence of excessive strain. A feature of note is that the device embodies but three parts all of which may be constructed as castings and on this account it is manifest that it may be manufactured at very little cost. It is moreover an important detail that there are no securing members of any sort and that no reliance is placed upon any springs. As normal swinging movement is permissible without release it is evident that there will be no friction between the holding down cam and the upper clamping member and as a result there will be no wear to cause a decrease in the gripping action even after tremendous prolonged use. It is thought from the above that the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A conductor supporting clamp comprising a body having a seat for receiving a conductor, an upper clamping member pivoted at one end within the body and engageable upon the top of the conductor, a suspension means connected with the body for supporting the same, a holding down cam pivoted within the body and having a cam surface engaging said upper clamping member, and means on said suspension means cooperating with said holding down cam for moving the same to release its pressure upon the upper clamping member upon swinging movement of the clamp beyond a predetermined limit, the pivots for the upper clamping member and the holding down cam being separate.

2. A conductor supporting clamp comprising a body having a seat for receiving a conductor, an upper clamping member pivoted at one end within the body and engageable upon the top of the conductor, a suspension means connected with the body for supporting the same, a holding down cam pivoted within the body and having a cam surface engaging said upper clamping member, means on said suspension means cooperating with said holding down cam for moving the same to release its pressure upon the upper clamping member upon swinging movement of the clamp beyond a predetermined limit, said last named means providing projections on the confronting sides of the suspension means, and divergent arms on said holding down cam located at opposite sides of said projections in spaced relation thereto, the pivots for the upper clamping member and the holding down cam being spaced apart longitudinally of the clamp.

3. A conductor supporting clamp comprising a body having a seat for receiving a conductor, an

upper clamping member pivoted at one end within the body and engageable upon the top of the conductor, a suspension means connected with the body for supporting the same, a holding down cam pivoted within the body and having a cam surface engaging said upper clamping member, and means on said suspension means cooperating with said holding down cam for moving the same to release its pressure upon the upper clamping member upon swinging movement of the clamp beyond a predetermined limit, said upper clamping member and said holding down cam having integral means thereon pivotally received within the sides of the body.

4. A conductor clamp comprising a main body having a seat adapted to receive a conductor, an upper clamping member located between the sides of said body and engageable with the conductor, suspension means connected with the body for supporting the same, a cam located between the sides of the body and having a cam surface engaging said clamping member, and means on the suspension means engageable with said cam for moving the same out of clamping relation to the clamping member upon swinging movement of the clamp beyond a predetermined extent, said clamping member and said cam having integral trunnions thereon pivotally engaged within the sides of the body, and means on the sides of the body preventing disconnection of the clamping member and cam therefrom, under normal circumstances and enabling said clamping member and cam to be disconnected when in ineffective position with respect to the conductor.

5. A conductor supporting clamp comprising an elongated body having a seat between its sides for engagement beneath a conductor, the sides having circular openings communicating with slots opening out to the top, a clamping member engageable upon the conductor and provided at one end with trunnion lugs insertable through said slots and rotatably engageable within the openings, a cam pivoted between said sides and having its lower portion formed with a cam surface engaging said clamping member and having its upper portion provided with upstanding arms, suspension means for said body, and means on said suspension means located between said arms and engageable therewith for tripping said cam upon swinging movement of the device beyond a predetermined extent.

6. A conductor supporting clamp comprising an elongated body provided between its sides with a seat adapted to engage beneath a conductor, a clamping member pivoted at one end between said sides and engageable upon the top of the conductor, said sides being formed with circular openings communicating with slots opening out at the upper edges, a trip cam located between the sides and having trunnion lugs insertable through said slots and rotatably engageable within said openings, said trip cam having its lower portion formed with a cam surface engaging said clamping member for holding the same down upon the conductor and having its upper portion formed with spaced arms, suspension means for the body, and means on said suspension means located between said arms and engageable therewith for tripping said cam upon swinging movement of the clamp beyond a predetermined extent.

7. A conductor supporting clamp comprising an elongated body having a seat between its sides for engagement beneath a conductor, the sides having circular openings communicating with slots opening out to the top, a clamping member

engageable upon the conductor and provided at one end with trunnion lugs insertable through said slots and rotatably engageable within the openings, said sides being formed centrally with other circular openings communicating with slots opening out at the top edges, a trip cam provided with trunnion lugs insertable through the second named slots and rotatably engageable within the second named openings, said trip cam having its lower end formed with a cam surface cooperating with said clamping member to hold the same down, said trip cam having an upward extension, suspension means for the body, and means on said suspension means cooperating with the upward extension on the trip cam for releasing the same upon swinging movement of the clamp beyond a predetermined extent.

8. A conductor supporting clamp comprising a lower clamping member engageable beneath a conductor and having spaced upstanding sides, an upper clamping member disposed between said sides and bearing upon the top of the conductor, trunnion means formed integrally upon one end of the upper clamping member and removably and pivotally engaged within openings in the sides of the lower clamping member, and means mounted between the sides of the lower clamping member above the upper clamping member for maintaining the same normally in engagement with the conductor.

9. A conductor clamp comprising a lower clamping member adapted to receive a conductor and having spaced upstanding sides each formed near one end with a circular opening and a constricted slot leading therefrom to the upper edge of the side, an upper clamping member disposable against the top of the conductor and lying between said sides, said upper clamping member being provided at one end with trunnions movable along said slots when the upper clamping member is in disengaged relation to the conductor and rotatably engaged within said circular openings when the upper clamping member is in clamping relation to the conductor, and means reacting against the intermediate portion of the upper clamping member for normally maintaining its clamping relation.

10. A conductor clamp comprising a lower clamping member adapted to receive a conductor and having spaced upstanding sides each formed near one end with a circular opening and a constricted slot leading therefrom to the upper edge of the side, an upper clamping member disposable against the top of the conductor and lying between said sides, said upper clamping member being provided at one end with trunnions movable along said slots when the upper clamping member is in disengaged relation to the conductor and rotatably engaged within said circular openings when the upper clamping member is in clamping relation to the conductor, and means reacting against the intermediate portion of the upper clamping member for normally maintaining its clamping relation, said means being detachable when in ineffective position.

11. A conductor clamp comprising a lower clamping member adapted to receive a conductor and having spaced upstanding sides each formed near one end with a circular opening and a constricted slot leading therefrom to the upper edge of the side, an upper clamping member disposable against the top of the conductor and lying between said sides, said upper clamping member being provided at one end with trunnions movable along said slots when the upper

clamping member is in disengaged relation to the conductor and rotatably engaged within said circular openings when the upper clamping member is in clamping relation to the conductor, and means reacting against the intermediate portion of the upper clamping member for normally maintaining its clamping relation, said means comprising a holding down cam pivoted between said sides and disengageable therefrom when in ineffective position.

12. A conductor clamp comprising a lower clamping member adapted to receive a conductor and having spaced upstanding sides each formed near one end with a circular opening and a constricted slot leading therefrom to the upper edge of the side, an upper clamping member dis-
5 posable against the top of the conductor and lying between said sides, said upper clamping member being provided at one end with trunnions move-
10 able along said slots when the upper clamping member is in disengaged relation to the conductor and rotatably engaged within said circular open-
15 ings when the upper clamping member is in clamping relation to the conductor, and means
20 reacting against the intermediate portion of the upper clamping member for normally maintaining its clamping relation, said means comprising a holding down cam having oppositely extending trunnions with flattened sides normally rotatably
25 engaged within circular openings in said sides, said sides having slots leading from said last
30 named circular openings to the upper edges to permit passage of said second named trunnions when said holding down cam is in ineffective position.

13. A conductor clamp comprising a lower clamping member adapted to receive a conductor and having spaced upstanding sides, an upper clamping member located between said sides for engagement with the top of said conductor, and a holding down cam mounted between said sides and reacting against said upper clamping member for maintaining it normally in clamping relation to the conductor, said holding down cam being formed with oppositely extending trunnions having flattened sides, and the sides of the lower clamping member being formed with circular openings and reduced slots leading therefrom to the upper edges, said circular openings receiving said trunnions when the said holding down cam is in normal or effective position reacting against the upper clamping member and being withdrawable through said slots when the holding down cam is partially rotated into ineffective position with respect to the upper clamping member.

14. In a conductor supporting clamp, a lower clamping member for receiving a conductor and having upstanding sides, suspension means connected with said lower clamping member, a hold-
60 down cam mounted between said sides and reacting toward the conductor, and an upper clamping member located between the sides and beneath said cam for engagement with the conductor, and means pivotally connecting one end of said upper clamping member to the sides of the lower clamping member, said means being formed as integral lateral projections on the upper clamping member received within openings in said sides.

15. In a conductor supporting clamp, a lower clamping member for receiving a conductor and having upstanding sides, suspension means connected with said lower clamping member, a hold-

down cam mounted between said sides and reacting toward the conductor, and an upper clamping member located between the sides and beneath said cam for engagement with the conductor, and means pivotally connecting one end of said upper clamping member to the sides of the lower clamping member, said means being formed as lateral projections on one end of the upper clamping member, said sides having keyhole slots receiving said projections and permitting withdrawal thereof when the upper clamping member is swung away from the conductor.

16. In a conductor supporting clamp, a lower clamping member for receiving a conductor and having upstanding sides, suspension means connected with said lower clamping member, a hold-
15 down cam mounted between said sides and reacting toward the conductor, and an upper clamping member located between the sides and beneath said cam for engagement with the conductor, and means pivotally connecting one end of said upper clamping member to the sides of the lower clamping member, said means being formed as lateral projections at one end of the upper clamping member, said projections having
20 two opposite sides flat and their opposite edge portions curved, said sides having curved openings rotatably receiving and retaining said projections and further having reduced slots extending from said openings to the upper edges of the sides
25 of the lower clamping member for permitting passage and withdrawal of said projections from engagement with the lower clamping member when the upper clamping member is swung on its pivot away from the conductor.

17. In a conductor clamp, a lower clamping member for receiving a conductor and having spaced upstanding sides, an upper clamping member located between said sides for clamping engagement with the conductor, a hold-down cam located between said sides for cooperation with the upper clamping member to hold the same in engagement with the conductor, and means integral with said cam and rotatably and detachably engaged within openings in said sides.

18. In a conductor clamp, a lower clamping member for receiving a conductor and having spaced upstanding sides, an upper clamping member located between said sides for clamping engagement with the conductor, a hold-down cam located between said sides for cooperation with the upper clamping member to hold the same in engagement with the conductor, and lateral projections carried by said cam and rotatably and detachably received within keyhole slots in
55 the sides of the lower clamping member.

19. In a conductor clamp, a lower clamping member for receiving a conductor and having spaced upstanding sides, an upper clamping member located between said sides for clamping engagement with the conductor, a hold-down cam located between said sides for cooperation with the upper clamping member to hold the same in engagement with the conductor, projections extending laterally from both sides of said cam, said projections having diametrically opposite sides flat and their opposite edges curved, and said sides having circular openings receiving and normally containing said projections and further having reduced slots leading from the openings to the upper edges for permitting passage and withdrawal of the projections when the cam is rotated out of its normal position.
